CLAIM

The ornamental design for a camera housing, as shown and described.

DESCRIPTION

FIG. 1 is a bottom, front and left side perspective view of a camera housing showing our new design;

FIG. 2 is a top, rear and right side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The broken lines depict portions of the camera housing in which the design is embodied that form no part of the claimed design.

1 Claim, 7 Drawing Sheets
